UNITED STATES PATENT OFFICE.

CLYDE C. BALSTON, OF NEW YORK, N. Y.

WORD-WRITING MACHINE.

Application filed April 18, 1922, Serial No. 555,385. Renewed April 17, 1924.

This application is a duplicate of my prior application #505,258 which was a renewal of application #324,643, which was a duplicate of application 250,380 which was a renewal of application 839,965, May 21, 1914.

This invention relates to a type word-writing machine and it comprises:

First: A means for producing by the single depression of a key, and in some cases the depression of a shift key, whole words, groups of characters of any kind, and groups of small words or phases, with the spacing between such words, of all words and groups of characters in ordinary use.

Second: A means for producing all single characters by the depression of keys corresponding therewith, numerical and other characters being produced by the same keys.

Third: A means whereby two keys constitute one in a compound key, thereby lessening the number of independent single character keys, to thirteen.

Fourth: A means for automatically spacing the carriage a number of spaces corresponding with and one space more than the number of characters in a word, the said feed being a variable feed which actuates the carriage according to the length of any group of characters, and which is also actuated by the depression of character keys.

Fifth: A means whereby a number of hammers are automatically operated, also by the depression of a character key, the said number of hammers operated being equal to the number of characters in a designated word.

Sixth: Means whereby the carriage may be moved forward immediately a designated number of spaces, the said movement being independent from the movement of a character key.

Seventh: An automatic construction whereby the carriage when it reaches the end of a line, is returned from the end of such line to the beginning thereof, also means for returning the carriage mechanically from any position it may occupy on a line, and a means for automatically feeding the paper one or more line spaces, with the return of the carriage to the beginning of a line.

Eighth: A means whereby an ink ribbon is fed alternately in a forward and backward direction, with the forward and backward traveling of the carriage, but more in one direction than in the other direction until the ribbon is wound entirely upon one reel, when the binding of the ribbon, thus wound, automatically shifts a mechanism which causes it to wind more upon the other reel and in the opposite direction, until entirely wound thereon; the operation being repeated with the continued movement of the carriage.

Ninth: A power mechanism operating mechanism of the machine; the said mechanism being set in operation by the depression of a character key, and governed by a governor, and a means whereby an alignment lock, when in engagement with the type supports, and when having locked the same, causes the action of mechanism for impressing the type set, and the feeding of the carriage forward after such impression.

Tenth: A synchronizing mechanism for evenly depressing transverse bars for simultaneously operating a plurality of type supports when the said bars are actuated by a character key.

Eleventh: A means for shifting transverse bars simultaneously and laterally across a type operating mechanism to change combinations of words.

In order that this invention may be properly understood and explained in detail, I have annexed hereto sheets of drawings in which

Fig. 1 is a front elevation of the machine, showing the key bed in longitudinal section, about on the line 2—2 of Fig. 7.

Fig. 2 is a side elevation of the machine, partly in section and with key bed removed, and key levers broken away.

Fig. 3 is an enlarged top reversed view of a part of the governor for controlling the action of the stored power for actuating the machine.

Fig. 4 is an enlarged side elevation of Fig. 3, partly broken away.

Fig. 5 is an enlarged cross-sectional view of a ribbon feed rack and a portion of its supporting mechanism.

Fig. 6 is a broken view of the end of a le-

ver, supporting a device for releasing the governor catch of Figs. 2, 3 and 4.

Fig. 7 is a side elevation of the key bed with side plate removed, and with the key 5 levers partly broken away.

Fig. 8 is a detail view of a portion of the synchronizing mechanism.

Fig. 9 is an enlarged top view of a word key, minus words.

10 Fig. 10 is a side sectional view of a word key, attached to a stem, partly broken away.

Figure 11 shows a stem enlarged and partly broken away, and the manner of attachment to a transverse bar, which is also 15 broken away.

Figure 12 is an end view of Fig. 11 with a pin set in position in a transverse bar.

Fig. 13 is a top view of a transverse bar, with pin holes, and showing the stem cross- 20 sectionally on the line 5'-5' of Fig. 12.

Fig. 14 is a side elevation of the end plate of the key bed, broken away, with a covering over said plate, partly broken away, and shows the position of transverse bars, and of 25 springs and means for their support.

Fig. 15 is a side elevation of a guide for certain of the transverse bars of the key bed.

Fig. 16 is a plan view of the key bed with the keys removed, showing a number of 30 transverse bars in position relative to the type operating levers, which levers are shown partly broken away; it further illustrates the position of the pins in said transverse bars and means for supporting and limiting the 35 movement of the keys for operating characters and shifting laterally the position of the transverse bars.

Fig. 17 is a detached end view of a key for 40 instantly imparting a variable feed to the platen.

Fig. 18 is a plan view of the complete keyboard showing the arrangement of characters and the relative arrangement of words upon keys, as represented by the dotted lines 45 thereon; it also shows the shift keys for laterally shifting the keys and transverse bars; the type operating levers are here shown broken away.

Figs. 19 and 20 are enlarged plan view of 50 a word key, and show an arrangement of words thereon.

Fig. 21 is a side elevation of the key bed, with the end plate removed, to show the position and manner of operation of single 55 character keys.

Fig. 22 is a front elevation of a portion of a transverse bar, in depressed position, showing the action of its pins of different lengths (according to the scale as shown) 60 upon type operating levers, which are shown in cross section.

Fig. 23 is a broken view of a transverse bar, enlarged, showing constructions of the said bar, and plain and threaded pins in position,

Fig. 24 is a vertical section of a combination single character key, taken on the line 7-7 of Fig. 25;

Fig. 25 is a vertical section of the key of Fig. 24, and is taken on the line 8-8 of 70 said figure.

Fig. 26 is a cross section of a pin for the inner key, and a tube for the outer key, of Figs. 24 and 25.

Fig. 27 is a cross section of the strip 75 secured to the inner key, and of the sheath secured to the key of Figs. 24 and 25, and is taken on the line 9-9 of Fig. 25.

Fig. 28 is a cross section of the part shown in Fig. 27, slightly modified, and is taken 80 on the line 10-10 of Fig. 25.

Fig. 29 is a vertical view partly broken away of a modified form of type support, and means for operating the same.

Fig. 30 is a plan view of Fig. 29, partly 85 broken away.

Fig. 31 is an enlarged broken view of a portion of the type support of Fig. 29.

Fig. 32 is an enlarged end view of the type 90 support of Fig. 30.

Fig. 33 is an enlarged plan view of a guide, partly broken away, of Fig. 30.

Fig. 34 is an enlarged plan view, partly 95 broken away, of a modified form of a hammer.

Fig. 35 is a top view, partly broken away, showing a group of hammers, of Fig. 34.

Fig. 36 is a plan view, partly in section, and partly broken away, of the type supports and hammers therefor, the ribbon reels 100 and feed mechanism therefor, and the variable feed and automatic release mechanism for the carriage.

Fig. 37 is an enlarged sectional view of a portion of the feed release mechanism of 105 Fig. 36.

Fig. 38 is an enlarged perspective view, 110 partly broken away, of the means for automatically releasing the carriage to allow its return for the beginning of a line.

Fig. 39 is a side section, taken on the line 11-11 of Fig. 40, of a guide and friction mechanism for placing a tension upon the ink ribbon, and is swivelled to a support 115 partly broken away, and shows a portion of said ink ribbon in operative position.

Fig. 40 is a plan view of Fig. 39, with the ink ribbon and support removed.

Fig. 41 is a detail view of a portion of the top plate of the ribbon reel, and shows the 120 means for locking the same to the reel rim.

Fig. 42 indicates a portion of the double end of an ink ribbon to be attached to the ribbon reel, shown cross-sectionally in Fig. 43, which is taken on the line 12-12 of Fig. 125 36.

Fig. 44 is a plan view of the mechanism for operating the carriage feed and printing mechanism, and is a continuation of Fig. 16. It shows a device for storing power for 130

operating the said mechanism, and for governing the use of the said power; it also illustrates a portion of the variable feed mechanism for the platen.

5 Fig. 45 is a rear elevation of the variable feed mechanism, hammers and connecting parts thereto, partly broken away, the platen and carriage and means for actuating the same in forward and backward movements; 10 also means for imparting a variable movement by the hand by depressing the key of Fig. 17, part of the connections leading to which are here shown.

15 Fig. 46 is an enlarged end view, partly broken away, of the carriage for carrying the platen and a means for automatically rotating the platen one or more spaces.

20 Fig. 47 is an enlarged broken perspective view of a portion of the angular arm partly broken away, of Figs. 45 and 46, to intercept the spurs, radiating from the platen shaft of Fig. 46.

25 Fig. 48 is a perspective detail view of a set pin for facilitating the action of the hammers.

Fig. 49 is a vertical detached view of a type support and means for operating and guiding the same, which are broken away.

30 Fig. 50 is a vertical edge view of Fig. 49 shown sectionally on the lines 13—13 and 14—14 of said figures.

Fig. 51 indicates a type strip having characters arranged thereon.

35 Fig. 52 is a broken sectional view of a portion of the type support of Fig. 49, showing a type strip with type formed thereon, secured to said support.

Fig. 53 indicates a type strip having alphabetical characters arranged thereon.

40 Fig. 54 is a top view showing a plurality of the type supports of Fig. 49 upon a shaft.

Fig. 55 is an enlarged vertical section of a type lever and type support operating mechanism broken away, and is taken on the 45 line 14—14 of Fig. 49.

Fig. 56 is an enlarged view of a power transmitting mechanism of Fig. 2, and represents levers in operative connection therewith, and broken away.

50 Fig. 57 is a plan view, partly broken away, of a device for engaging and disengaging a lever with two type supports.

Fig. 58 is an end view partly in perspective and broken away, of Fig. 57.

55 In the figures A indicates the machine frame to which are pivoted at *a* type supports *A*¹ (here shown in the form of wheels). Secured to each type wheel *A*¹ is a pinion *a*¹, which is operated by a rack *A*², which rack passes through a guide *a*² at its lower end, and is held in position by a guide rod *a*³. The said rack *A*² is pivoted by a pin *a*⁴ in a hole or lateral slot *a*⁵, each to a lever *A*³, which lever is pivoted to a shaft *a*⁶, and continues as at *A*⁴ beneath the key

bed *A*⁵. The said lever *A*⁴ is joined as at *a*⁷ to a part *A*⁶, which is pivoted at its end *a*⁸ to the bed *A*⁷ of the machine. The parts *A*⁴ and *A*⁶ constitute a single lever, a plurality of which are here employed. These levers are arranged an even distance apart, and in parallel lines, between the pivots *a*⁶ and *a*⁸. These levers are secured to a block *A*⁸ which is loosely supported by the shaft *a*⁶. To the opposite end of each of these blocks are secured the levers *A*³ which converge into parallel lines to form the extensions *A*⁹ which connect loosely with the racks *A*², and the carriage feed mechanism, which will be described later. The outer blocks *A*⁸ may be provided with loosely interlocking positions *a*⁹, *a*¹⁰ for the purpose of facilitating the converging of the levers *A*³.

Over the levers *A*⁴ *A*⁶ is a key frame *B* forming guides *b* *b* and adapted to shift laterally across the said levers by means of rollers *b*¹ having flanges *b*².

Within the said frame *B* and arranged longitudinally and adapted to shift therewith, are transverse bars *B*¹, which bars are provided with pins *b*³, preferably threaded as at *b*⁴ (as clearly shown in Fig. 23), the said bars *B*¹ being preferably shaped in cross section, having longitudinal flanges *b*⁵ *b*⁶, and provided with a series of holes *b*⁷ (Figs. 13 and 16) extending through both flanges. The holes in one of the said flanges of the bar *B*¹ are threaded to receive for adjustment the threaded end *b*⁴ of the pins *b*³. But the pins *b*³ may also be forced into a solid bar, as at *b*⁸. These pins are set at various heights, as shown in Figs. 1 and 22, the latter view showing a bar *B*¹ depressed on to the frame *A*⁵, which in said Fig. 23 is represented by dotted lines. It is thus seen that since each lever operates a type support, and that the degrees of depression imparted to a lever by operating through the mechanism leading to the type supports, as described, will actuate said supports according to the depth or depths to which said levers may be depressed and move designated type corresponding to such depressions, into printing position. Fig. 22 represents a number of type operating levers, as shown by *A*⁴, depressed to varying depths by the pins of the said transverse bars, and the even seating of the said bars which would cause a number of type corresponding with the depression of said levers, to move into printing position.

100 The transverse bars *B*¹ are held upward against an under edge *b*⁹ of the frame *B*, by means of springs *c*, bent over and held in position by a bar *C*¹, which is secured at *c*² to a plate *b*¹⁰ (see Figs. 1, 14 and 18), the said springs *c* being secured to the said plate *b*¹⁰, as at *c*³ and projecting through the plate *b*¹⁰, and in between and against the transverse bar *B*¹ to hold it in upward position.

110

115 The transverse bars *B*¹ are held upward against an under edge *b*⁹ of the frame *B*, by means of springs *c*, bent over and held in position by a bar *C*¹, which is secured at *c*² to a plate *b*¹⁰ (see Figs. 1, 14 and 18), the said springs *c* being secured to the said plate *b*¹⁰, as at *c*³ and projecting through the plate *b*¹⁰, and in between and against the transverse bar *B*¹ to hold it in upward position.

120

125

130

These plates b^* also serve as guides to the ends c^4 of the transverse bar B^1 . To each of the transverse bars B^1 is attached a word key C by means of strips c^5 , which strips 5 may be split and secured to each side of said bar, as at $c^6 c^7$, or secured as at c^8 , or in any different manner. To insure the even depression of a bar, when a key may be located considerably at one side of the longitudinal 10 centre thereof, a synchronizing mechanism is employed, which consists of levers D , pivoted at d to projections d^1 of the frame B . A connecting piece d^2 connects pivotally at $d^3 d^4$ the two levers together. The opposite ends of the said levers support each a pin which passes loosely into a slot d^4 . This construction is such that when any key attached to a bar, is depressed and thereby 15 depresses the transverse bar B^1 , by means of the slots d^4 in said bar and the pins in the levers D which fit into said slots, the lever nearest to the said key depressed upon the said bar, by means of its corresponding pin and slot, is actuated to move the bar d^2 connecting the levers D together, and thereby 20 simultaneously actuates the other lever D near the opposite end of the bar B^1 by means of its corresponding slot and pin, to move the bar evenly down--other means 25 than this may also be employed to the same end. The pins b^3 in the transverse bars B^1 are arranged equal distances apart corresponding with the distances the type operating levers are spaced apart. There 30 are thirteen type operating levers here shown. (The number however may be increased or diminished). If a designated word contains a less number of characters than there are type operating levers, only 35 as many pins are placed in the bar for the production of such word and to operate such levers, as there are characters in said word. This is illustrated in Fig. 22. A key is provided with several words. The series of 40 pins as shown in Fig. 22 represents the first word upon said key. For the second word to be produced by said key and its bar, a second series of pins d^5 are arranged equal spaces apart, the said spaces corresponding 45 to the spacing of the first series of pins, the first pin of the second series beginning next in order to the first pin of the first series, as shown in Fig. 1. The first pin of the third series d^6 begins back of the first pin of the 50 second series, and so on with as many series 55 of pins (corresponding with the number of words upon a key) as there are spaces for said pins between each lever (the number here shown being ten series to a bar). 60 A means for simultaneously shifting the bars B^1 for bringing one of the series of pins for the production of a designated word into position, is shown in Figs. 1, 7, 16 and 18, and consists of a number of stop or shift keys D^1 , which keys pass through adjustable

gauges $d^7 d^8$, preferably threaded and adjustable in a portion of the key bed frame A^5 . These keys D^1 are provided with pins d^9 which rest upon a portion of an angular lever D^2 pivoted at d^{10} to the frame A^5 , or to the machine bed A^7 . An opposite end D^3 of the lever D^2 is loosely connected by means of a slot and pin d^{11} , or other mechanism, to a portion of the rolling frame B which carries the transverse bars. A set screw D^4 is 70 made adjustable in said frame to limit the extreme lateral movement thereof against the frame A^5 ; another set screw D^5 corresponding therewith and at the opposite end of the frame B is made adjustable therein 75 and against the frame A^5 to limit the backward movement of the frame B and the transverse bars B^1 . 80

Each of the word keys C is provided with a number of words (Fig. 18) which are arranged in alphabetical order thereon, and are also arranged upon said keys under a designated initial character, as for instance the large character A upon the first word key, the said character A answering for all words 85 beginning with A upon the immediately following keys; the character B , upon the first of the keys having words beginning with B , and so on throughout the alphabet, a number 90 of keys corresponding with the number of words ordinarily used beginning with a certain initial character being employed for words beginning with such initial character. 95

This arrangement is not essential to the proper working of the machine, as all words beginning with a certain initial character may be grouped together irrespective of the larger designations, A , B , C , D , &c. The words placed upon each key are arranged according to style of character, or background 100 and position. Each word key is preferably divided by a dividing line C^1 , passing centrally across the face thereof, the first word on every key, as shown in Figs. 19 and 20, 105 representing the arrangement of words on two keys beginning with the initial character A , is here shown in a thin type on a white ground, the second position word on every key is a heavy character on a white ground, the third position word is a white character 110 on a black ground, the fourth position word is a medium character on a shaded or tinted ground, and the fifth position word on every key is an open character on a lightly shaded ground. This arrangement of words according to style of character, and shade or tint of background may of course be varied as desired, or to facilitate manipulation. 115

The words below the dividing line C^1 on each key repeat the order and style of character and background of the words above the said line. 120

The shift keys D^1 , numbers 2, 3, 4 and 5 correspond in the style of character and background with the words occupying the 125

second, third, fourth and fifth positions upon the word keys. Since the transverse bars are always normally in position to produce the first word on every key, no shift key is required for the first word upon each key; but since the first word below the dividing line of each key is practically in the sixth position with relation to the operation of the machine, the arrangement of the words below the line and the shift keys corresponding therewith, being the same as the words above the line, the order of the shift keys, for such words below the line, is simply repeated to facilitate operation, and the number 1 shift key is made to represent the first word below the line, and so on with the remaining keys.

Between the keys C and made flush with or raised a little above the surface thereof, are placed dividing strips C² which form between them cells for the reception and separation of the said keys C. These strips may be adjusted in any suitable manner to accommodate the said result, which is primarily to prevent accidental depression of other keys than the one containing the designated word or words.

Running laterally across and beneath the transverse bars B¹ is a piece E supporting strips or thin plates e, Figs. 1 and 15, which strips are arranged a sufficient distance apart to permit of the transverse bars passing loosely between them; the top edges e¹ of the said strips being adapted to serve as rests or limits to the said transverse bars by the bottom edge of the latter resting thereon when depressed. This device is to prevent the undue springing of a bar when depressed by a key which is attached near its central portion.

Within the frame B are secured parallel guides F which are fitted with (preferably) threaded adjustable gauges F¹. These gauges are provided with holes f through which extend key pins F² which are in position immediately above the levers A⁴. These keys, as shown in Fig. 21, are arranged from the shaft a⁶ over the said levers A⁴ to the pivot a⁸. They represent the single character keys, and consist of a key within a key, Figs. 24 and 25 sectionally illustrating the construction thereof. They are depressible to different depths according to their positions and corresponding with their designated characters, as limited by the gauges F¹. The construction employed in these keys is that of an outer key F³ having a depressed area f¹ with a bevelled top edge f² and a tube or sheath F² (Figs. 24, 25 and 26) extending therefrom and through the said gauges F¹. Within the area f¹ and below the surface of the key F³ is placed a smaller key F⁴ having preferably a convex surface f³. From the key F³ extends a strip or pin f⁴ which passes loosely through the sheath or tube F², and is in position above the levers A⁴, A⁶, its

bottom end being flush with the bottom end of the tube or sheath F². A preferable construction of this device is that of employing a thin strip for the inner key extension, and a flat sheath for the outer key extension. The said key extensions, in the construction here shown, pass between and in the spaces between the transverse bars, though this is not actually necessary. The lower ends of the extensions F² and f⁴ may be bevelled in order that the two may be held together. In Fig. 24 is seen a spring f⁵ which is of a weak construction and is designed to merely support the weight of the inner key in order to keep the lower ends of both stems even.

The gauges F¹ are preferably tubular in construction with a reduced opening at their lower ends, and within their said tubular portions, and around the sheaths or tubes F² of the keys are placed spiral springs f⁷ which bear against the under part of the keys F³ to hold them in upward normal position. Between the said keys are placed division strips F⁶ which form cells to receive and separate the said keys; the said strips being made flush with or raised above the surface of the said keys. The levers A⁴ A⁶ are held even spaces apart on the shaft or pivot A⁸, which is held in position by supports F⁸, by means of collars F⁷ which are adjustable preferably by means of screws f⁸, see Figs. 16 and 18.

It will be seen, by referring to Fig. 18 that all of the vowels fall upon the inner keys, and that the consonants are placed upon the outer keys, the arrangement of the type upon the supports, since the inner keys have a greater movement than the outer keys, corresponds in order with the arrangement with the characters upon said keys, the characters running in the order B A, D C, F E &c., the order of the type upon the type supports, Fig. 49, corresponding with the arrangement of characters upon the keys.

If desired the order here shown may be so changed that the outer keys will have the vowels and the inner keys contain the consonants, thus causing the said letters to read in alphabetical order A to Z, when the type upon the type supports would be arranged to correspond therewith, as shown in Figs. 53 and 54. For the production of numerals, punctuation and other signs an extra type support (as shown in Fig. 50) may be provided, which support, fitted with such characters, shown in Fig. 51, is journaled upon the shaft before and with the supports bearing the alphabetical characters.

A support, A² similar to that employed in the operation of the other type supports, Fig. 50, is employed to operate said first positioned support, and a means is provided whereby the said support may be thrown into or out of operation. This means consists of a lever A^{3*} which from its flexibility, or a

hinge g , may by any efficient means be swerved in one direction, to engage said first support, and disengage the second support, and if swerved in the other direction, disengage the first support and engage the second support, as shown in Figs. 50 and 55. A pin g^1 is secured to said lever A^{3*} , which may pass alternately into a slot g^2 of the first piece A^2 , or into a slot g^3 of the second piece A^2 . This lever A^{3*} may be operated by means of a spring lever G secured thereto, which is provided with a finger push g^4 , which finger push is in frictional contact with a catch piece C^1 , secured to a lever block A^{3*} , the said piece C^1 being provided with nicks g^5 , into which nicks is adapted to movably fit a pointed or sharpened edge g^6 of the lever G . It is thus seen that if the lever G is pushed and caught in forward position the lever A^{3*} by means of its pin g^1 will engage and operate the second support A^2 , which will operate the first support bearing letter characters. If the lever G is drawn backwards, the lever A^{3*} , as described, will be thrown out of engagement with the said letter support mechanism A^2 , and will be thrown into engagement by means of the pin g^1 and slot g^2 with the mechanism for operating the first support, which bears the numerical and other characters.

It is thus seen how the single character keys, shown in Fig. 18, since the arrangement of all characters upon such keys correspond with the arrangement of type upon the said supports, may produce, or may move into printing position, any of said characters that they may represent.

The transverse bars B^1 are preferably held from frictional contact with each other, and guided in their downward movement by parallel strips B^2 , secured in the frame B , Fig. 14.

Fig. 29 represents a modification of the type support, and consist of a strip H , having type h arranged longitudinally along one surface, and guided by guides h^1 in front of a brace h^2 , a rack h^3 running longitudinally along the back of said strip. Each of the said strips H are operated by a cog wheel H^1 which is pivoted upon a shaft α^* and operated by racks H^2 which correspond with the racks A^2 and operate upon pinions h^3 secured to the said wheels H^1 .

I do not limit myself to this construction shown, or to any construction to accomplish the end herein set forth, as I am aware that such construction can be modified in many ways to produce a similar result, it being needless to express more than sufficient to demonstrate the desired result attainable.

The feed employed in the operation of this machine is such that the mechanism will always produce one space more than the number of characters in a designated word set. This same construction, with a slight altera-

tion, is capable of producing a movement equivalent to only the exact number of characters in a word, but it is desirable to have the machine automatically produce the space between the words. This construction is what I term a self differentiating feed device, since the said feed is differentially set by the difference in action as to the number of the type supports operating mechanisms upon the dogs of said feed, which causes them to be differentially set and consequently to make a different action upon the feed to move the carriage a different number of spaces according to the number of type set for a word. One manner of accomplishing this result is set forth in Figs. 2, 36, 44 and 45, in which the continuations A^9 of the levers A^3 are pointed as at i to operate upon feed set pieces I which are pivoted to small pins at i^1 and which normally occupy a horizontal position when the levers A^3 occupy a normal position. These pieces I are of graduated lengths and correspond in number with one space more than the number of characters in a designated word. They are supported pivotally at i^1 by a double lever I^1 which is pivoted at i^2 to a portion of the machine frame or bed. Below the pivot i^1 is secured to the said levers a plate I^2 which is provided with steps i^3 corresponding with or one less than the number of pieces I , and back of the said piece I^2 is a stop piece i^4 which limits the swing of the pieces I to a vertical position when actuated by the point i of the levers A^3 A^9 . The object of the plate I^2 is to take the strain from the pivot i^1 which is exerted upon the said pivot and the pieces I when the latter are set in vertical position to operate upon the edge I^5 of the feed plate I^3 when the said pieces I are actuated by the lever A^3 .

The smallest of the pieces I , marked in Fig. 45 i^0 correspond with and is operated by the first position type operating lever. The second piece i^7 corresponds with and is operated by the second lever. The third piece i^8 is operated by the third lever. The fourth piece i^9 is operated by the fourth lever. Having a pressure upon the lower plate I^4 of the lever I^1 is a spring I^6 secured at i^{10} to a portion of the machine frame or bed, which spring has a set screw I^6 bearing upon an extended end thereof, as a means for placing a tension upon said spring and lever I^1 , to hold the latter in downward or normal position at the plate I^2 . The before mentioned plate I^3 which actuates the feed by means of the construction just described, is provided here with extended portions j j which pass through guides j^1 j^2 . This plate is movable longitudinally in said guides and has secured to it a piece J which is pivotally connected with said plate at j^3 . The opposite end of said connecting plate J engages pivotally at j^4 with a piece J^2 which is piv-

oted to a shaft J^3 . The piece J^2 supports by means of the pivot j^5 a cam or eccentric J^4 . This cam or eccentric J^4 is provided with a weight j^6 , and frictionally engages when moving in one direction a clutch J^5 , which is secured to said shaft. The shaft J^3 is journaled in a portion of the machine frame A , and has secured thereto a cog wheel J^6 which meshes with a rack J^7 which is pivotally attached at j^7 to a portion of the carriage frame K . Supported by and loosely pivoted upon the shaft J^3 is another cog wheel J^8 of the same dimensions and kind as the cog wheel J^6 . These two cog wheels are placed adjacent to each other, but the cog wheel J^8 , being loosely supported by said shaft J^3 is secured to and rotatable with a sleeve j^8 , to which sleeve is also securely fastened the friction wheel J^5 (see Fig. 36 top view, and Fig. 37 sectional view).

The cog wheel J^6 is secured on the shaft J^3 , and revolves therewith, to which shaft is also secured a drum J^9 , preferably having the flanges j^9 . To this drum is secured a cord or other flexible strip j^{10} which is wound upon the said drum by the action of the feed in rotating the friction wheel, which action moves forward the rack J^7 of the carriage frame K by means of the cog wheel J^8 ; this forward movement of the rack, since the cog wheel J^6 also meshes therewith, and consequently moves with the cog wheel J^8 , revolves the drum J^9 and winds the cord j^{10} upon said drum thereby raising the weight J^{10} until, when the carriage has reached the end of a line, a portion k of the carriage frame K bears upon and moves forward a plate or bar k^1 , which is slidably in guides k^2 of the machine frame A . This part k^1 is best illustrated in Fig. 38. It consists of a bar or rod, as stated, having an inclined slot with elongated parallel ends k^3 , into which slot loosely fits a pin k^4 of a lever K^1 , which lever is secured to a pivot or shaft k^5 , which has secured to it another lever K^2 provided with a preferably short prong k^6 and a long prong k^7 , which latter prong is provided inwardly with a spring k^8 . These prongs project one each side of the pivoted rack J^7 , and the spring J^8 is placed in light contact with the side of the said rack nearest to the friction wheel J^5 . It is thus readily seen that if the feed actuates the wheel J^2 to move forward the rack J^7 and consequently the carriage K , when the said carriage reaches the end of a line, the part k thereof will bear against and move longitudinally the bar k^1 , which by means of the inclined slot k^3 and the pin k^4 fitting therein, will move the lever K^1 , which in turn will move the lever K^2 , which by means of the spring k^8 upon the prong k^7 being caused to bear upon the surface nearest to the friction wheel J^5 of the pivoted rack J^7 , will swing the said rack upon its pivots j^7

away from and out of connection with the cog wheel J^8 , thus leaving it only in engagement with the cog wheel J^6 (the limit of its movement being such as to hold it in such position), when the weight J^{10} , having been raised, revolves backward by means of its cord j^{10} and the drum J^9 and the shaft J^3 , the cog wheel J^6 , which, still meshing with the rack J^7 , by the falling of said weight, carries the carriage back to its original position, at the beginning of a line, when the projection k^* strikes against the opposite end of the bar k^1 , which reverses the action of the levers K^1 and K^2 , and in the manner described, (though inversely) swings the rack J^7 back to its original position, and in engagement with the cog wheel J^8 ; this operation being repeated with each movement of the carriage, back and forth. It is also readily seen that the bar k^1 may be moved by the finger to cause the carriage to return to its original position at the beginning of a line from any position of its travel.

The carriage for carrying the paper, as here shown, consists of the ends K^3 which are held together by rods K^4 and K^5 . To these rods is secured a plate K^6 which is split longitudinally at the part k^9 , this split being directly in front of the space at which the type come to alignment for the production of a word. The rods K^4 K^5 slide loosely through bearing K^7 in the machine frame. Depending from the said carriage is a metal sheath or tube K^8 which is adapted to receive the paper, as shown at l , the said paper passing over the plate K^6 and between the said plate and the type supports, and between a roller L which is pivoted at l^1 to a portion of the carriage frame, and a roller L^1 which is pivoted as at l^2 to the carriage frame. To the end of the roller L^1 are secured preferably by means of a wheel L^2 , spurs l^3 , spaced even distances apart, and of an even length. These spurs are adapted with the backward movement of the carriage, to glide against a curved angularly arranged strip L^3 , (Figs. 45, 46 and 47), which strip revolves the roll L by means of the said spurs l^3 a number of spaces according to its position with relation to the said spurs. This strip L^3 is pivoted as at l^4 , and is preferably provided with a weight l^5 to hold it in one position, and a shoulder l^6 to limit its movement upon the pivot l^4 in one direction.

The object of a pivot to this strip is that the said strip may easily be moved out of its course to allow it to freely escape the spurs l^3 with the forward movement of the carriage. The part L^4 to which the said strip L^3 is pivoted is provided with slots l^7 l^8 , and is held movably in position by means of screws or pins l^9 l^{10} , and a catch spring l^9 which has projections which fit into nicks l^{10} in the piece L^4 ; a knob or other projec-

tion L^1 is secured to the said piece to enable it to be moved to and from the pivot l^1 of the roll L . When the strip L^3 is moved to a position as represented by the dotted lines L^5 , the spurs are able to glide upon its edge a distance sufficient only to revolve the roll L a distance corresponding with one space between writing lines, but when the strip L^3 is in position toward the pivot l^1 the leverage of the spurs l^3 , being diminished, in gliding against the strip L^3 , since the said strip then acts upon their pivot l^1 , it causes the said roll L to be revolved double the number of spaces, since the said spurs have still to travel over the same surface but at a less leverage than required to travel when the strip L^3 is in the position L^5 . To the pivot l^1 or to the spur wheel L^2 is secured a lock wheel L^6 , preferably provided with lock recesses and teeth l^{12} with which is adapted to lock a lock or pawl L^7 which is pivoted at l^{13} and is provided with a spring l^{14} secured to a portion of said carriage, and having a tension upon the said pawl L^7 , to hold it in engagement with locks l^{12} .

To the carriage frame is attached a rigid bar M running longitudinally across the front of the said carriage, and running longitudinally along said bar is a strip or sheath M^1 having ends M^2 which preferably pass each side of the said bar M , and above the same, thereby forming a slot in which is placed a spring m secured by a pin m^1 . These springs exert a pressure upon the bar M sufficient to hold the strip or sheath M^1 in set position upon the said bar. Secured loosely to the strip or sheath M^1 , at M^2 , by means of slots m^2 and pins m^3 , are two racks M^3 M^{3*} .

The teeth of the rack M^3 are inclined in the direction of the forward movement of the carriage, and the teeth of the rack M^{3*} are inclined in the reverse direction. Each of these racks are shorter in length than the length of the travel of the said carriage, and consequently do not act throughout the entire length of travel upon more than one of the ribbon feed reels, which longer action upon such reel is due to the position of the racks in relation to the said carriage. With these racks mesh ribbon reels M^4 and M^5 composed of a lower plate m^4 m^5 secured to a hub m^6 which is supported turnably upon pins m^7 , the top plates m^8 and m^9 of the said reels are provided each with oppositely inclined teeth m^{10} and m^{11} which mesh with their respective racks. The lower plates m^4 m^5 are preferably secured to the pin m^7 which is loosely supported in the frame. The ribbon N is furnished wound upon a reel composed of thin plate m^{8*} m^{4*} secured to a hub m^6 . From the said plate m^{8*} projects a pin m^9 , and through the said hub and plates is adapted to pass a pin m^{10} having a head

m^{11} . This construction, bearing the ribbon N is adapted to be placed between the upper and lower plates of the reel, the pin m^{11} thereby projecting through an opening m^{12} in the upper plate, and locking the said plate when the same is turned round, by means of a slot m^{13} , when the pin m^9 enters the slot m^{14} in the reel upper plate, and thereby holds said upper plate in rigid position. The pin m^{10} by means of the loop N^1 formed at the end of the ribbon also fastens the said ribbon to the hub m^6 . The ribbon is drawn from one reel and secured to the other reel with a wind in the opposite direction, as shown in Figs. 1 and 36.

Fig. 36 shows the ribbon N unwound from the reel M^4 and passing round a roll O pivoted at o and under a friction spring O^1 ; said roll and spring being swivelled at O^2 to a portion of the machine frame. The said ribbon passes from the roll O up over an inclined form o^1 . Figs. 1, 2 and 36, and around a form o^2 across the front of the type wheels (the said ribbon being wider than the said type) and passing over similar forms adjacent to the ribbon reel M^5 and connecting therewith.

Since the sheath or strip M^1 (Fig. 36) by means of the construction described may be shifted a space longitudinally on the bar M , which bar is secured to the carriage frame, and when so shifted will act on one reel and then on the other reel, as set forth, it is obvious that if the said strip M^1 with its ratchets is shifted toward the right hand side of the carriage, when the said carriage travels backward along the line in operation, the teeth of the ratchet M^{3*} will engage the teeth of the ribbon reel M^5 and the teeth of the ratchet M^3 will escape the teeth of the ribbon reel M^4 . The forward travelling of the said carriage will operate upon the reels in the reverse of the action just described, but since the racks are shifted to the right hand end of the carriage the rack M^{3*} being brought more into play with the ribbon reel M^5 will have an action upon it greater than the action of the ratchet M^3 upon the ribbon reel M^4 , thus though the ribbon is wound from one reel upon the other reel and back again with the movement of the carriage, it is gradually wound upon the receiving reel, which is now M^5 , by the difference in the action of the racks upon said reels; until the ribbon is almost entirely wound upon the reel M^5 , as shown in Figs. 1 and 36, when the double thickness N^1 near the end of the ribbon N passing under the friction spring O^1 , (Fig. 39 enlarged and detached view), the said spring ordinarily allowing only the single thickness of the ribbon to pass freely under it, receives a tension from said spring which checks the free travelling and movement of its doubled portion N^1 , thereby causing a binding of the said ribbon N by means

of its doubled thickness N^1 passing under the said spring thereby causing a binding of the said ribbon and reels, which is sufficient to move the racks M^3 M^{3*} by means of the stoppage of the winding of the reel M^3 during the continued movement of the carriage, which thus shifts the racks to the left end of the carriage which causes then the left hand rack to act longer upon the left hand reel 10 than the right hand rack acts upon the right hand reel, thereby alternately making each reel the receiving reel. Figs. 1 and 36 illustrate the position of the ribbon and mechanism at the moment when the binding of the 15 ribbon would cause a shift to the aforesaid racks.

A power device consisting of a coiled spring preferably contained within a box or drum, as shown at P , Fig. 44, is used for the 20 operation of the mechanism for causing imprint of characters and for feeding the carriage and ribbon. This spring operates upon a shaft p , to which shaft is pivoted a slotted cross head P^1 having an extension lever P^2 25 fitted therein which lever is provided with a limit p^1 for its movement. Operated by said P^2 and connected therewith, is a friction clutch or pawl p^2 , preferably pivoted as at p^3 , to operate upon a friction or toothed 30 wheel p^4 , secured to the shaft p for winding the said spring. A pawl p^5 , secured to a portion of the machine frame A loosely engages a lock wheel p^6 which holds the spring 35 in wound position. The wheel P meshes with the pinion P^3 which is secured to a cog wheel P^4 (preferably being about five times the diameter of the pinion P^3), the cog wheel P^4 meshing with another pinion P^5 which is 40 preferably pivoted upon the shaft p , and is secured to a cog wheel P^6 which meshes with a pinion P^7 secured to a shaft q . This gearing may of course be arranged differently, but the object is, with one winding of the 45 spring, to store sufficient power to perform as much writing as is ordinarily done in a day. To the shaft q are securely attached and adjusted to revolve therewith, curved spurs Q which are preferably formed in the shape of disks, as shown in Figs. 2, 7, 44 50 and 56, and to the same shaft is attached a worm wheel Q' which meshes with a worm Q^2 , secured to a revoluble post q^1 having governor arms q^2 with preferably extension weights q^3 . Any other suitable power and 55 governing mechanism may be employed. To the end of the post q^1 or worm Q^2 is attached a head Q^3 which is fitted and adapted to revolve inside of a portion of the machine frame designated q^4 which portion 60 is provided with an inclined face, high at q^5 and lower at q^6 , a catch stop q^7 (see Figs. 3, 4 and 44) is formed upon said face between the heights of q^5 and q^6 which thus forms another step at q^5 . Within the head 65 q^3 is preferably formed a slot passing dia-

metrically across the same, within which is placed a catch bar q^8 , which is pivoted at q^9 to the said head. A spring q^{10} is fastened to the head as at q^{11} , and bears upon the said bar q^8 to hold it in locked position. Adapted to raise or move the said bar q^8 to release it from the catch stop q^7 is a piece r pivoted and formed preferably as at r^1 , Fig. 6, and having a spring r^2 bearing upon the heel r^3 of the piece r . This arrangement allows of a lateral movement to the said piece, which piece, with the said spring, is secured to a lever R , which lever is pivoted movably to the shaft a^6 in the manner previously described concerning other levers, the said lever R continuing as at R^1 under the key board, and having an extending position R^2 which passes immediately under and has a contact with the edge of the transverse bars B^1 . This lever is pivoted at r^4 to another lever R^3 pivoted to the shaft or pivot a^8 , and having an extending end R^4 which also rests against the under edge of the transverse bars B^1 . The extended portion of these two levers form a straight edge in contact with said bars. Attached movably to one of the said levers, as at r^5 is a connecting rod r^6 which connects with a crank r^7 to operate a shaft r^8 , which shaft passes laterally (Figs. 7 and 16) under the key bed, and connects pivotally by means of cranks r^9 with connecting pieces r^{10} which connect each movably with a bar or strip R^5 pivoted at r^{11} , and extending parallel with and to the end of one of the single character key support and guide pieces F . To the said bar R^5 is loosely connected at r^{12} another lever R^6 which extends parallel with the lever R^5 , and is pivoted at r^{13} to the key bed frame. 95

Levers R^7 and R^8 are similarly constructed and arranged and connected with the shaft r^8 , see Figs. 16 and 21. These levers R^5 , R^6 , R^7 and R^8 are provided with different depths in steps, as shown at r^{14} , r^{15} and r^{16} , Fig. 21, the said steps being slightly raised above the gauges F^1 , which limit the movement of the single character keys. By this means the single character keys, when about fully depressed, actuate the rod r^8 and the catch q^8 of the governor head Q^3 . 110

To a crank on the shaft r^8 is movably secured by means of a pin and slot s a connecting rod S , which rod connects at s^1 movably with a pivoted supporting frame S^1 having parallel bars or rods S^2 which pass longitudinally directly under the lower edge of the single character keys to act immediately upon the governor Q^3 with the depression of either of said keys. The said rods S^2 may also serve as supports for the single character keys, by means of the connections with the shaft r^8 through the lever R^2 R^1 by means of a spring s^2 actuating the lever r . 120

A space key is shown in Figs. 16 and 17 whose object is to cause a movement to the 125

carriage of a designated number of spaces, by the single depression of said key; the key head t is secured to a strip T which may be flexible, or may be provided with a hinge t^1 and is fastened to a rocking bar t^2 pivoted to a portion of the machine frame or bed. A piece T^1 is formed as shown in Fig. 17, preferably having the upright posts t^3 and t^4 . The top ends of these posts are above the lower edge of the flexible or hinged piece T . The said piece T^1 is cut a varying number of depths, as shown by the numerals, 1, 2, 3, 4, 5, 6, 7, 8, 9, 10. Mechanism which will be immediately described, is connected to said key to impart a movement to the carriage corresponding with the number of spaces in depth to which the said key is depressed; for example: If the key is depressed until the lower edge of the piece T touches the part 1, the carriage will be moved forward one space, if the piece T is swerved to one side until it touches the stop or post t^4 and is then depressed, the number of spaces which the carriage will move will correspond with the numeral and depth of space nearest thereto, as shown by 5. Intermediate steps indicate each a respective number of spaces. If the piece T is swerved over 6 and depressed, the carriage will move six spaces, or if swerved to the post t^3 and depressed, the carriage will move ten spaces. This construction of course may be arranged for any number of spaces. The shaft t^2 connecting with the piece T of the key t passing from the key board, bears a lever T^2 connecting movably by means of a rod t^5 with a bell crank t^6 , one of whose levers bears upon or connects with the ends t^1 of a rod T^3 which is provided with a spring t^8 bearing against a collar t^9 and a portion u of the machine frame. This spring t^8 holds the rod T^3 and piece T in normal position. Connected pivotally to the rod T^3 at u^1 is a connecting rod u^2 which engages movably at u^3 with a part U pivoted to the shaft J^3 ; the said piece U bearing an eccentric U^1 or other clutch to engage the friction wheel J^5 and rotate the same when operated by the key t . This clutch U^1 when in normal position also serves to prevent the accidental backward movement of the carriage when operated by the machine, and the clutch J^4 , Figs. 36 and 45 serves as a preventive for the accidental backward movement of the carriage when the same is moved forward by the key t . Placed in a parallel line opposite to the type supports are as many hammers or impressers V as there are type supports. These hammers are provided with enlarged ends or heads v . Figs. 2, 36 and 45, having projections v^1 or having claws v^2 adapted to movably hold hard rubber discs v^3 , see Figs. 34 and 35. These hammers V preferably consist of

straight bars held in parallel guides v^4 and are provided with heels v^5 , and with springs v^6 secured to the machine frame as at v^7 and having a means v^8 for adjusting the tension thereof. A finger key v^9 may be secured to said hammers to impart an impression by drawing the hammer back, thereby allowing it to strike against the paper to print or reprint an accidental missing or corrected type without operating the entire power. Bearing against heels v^5 of each of the said hammers, are bell cranks V^1 pivoted as at v^9 to a portion of the machine frame. These cranks correspond in number with the number of hammers. Movable secured to one lever of each of the said cranks are rods V^2 which depend therefrom and are provided with feet shaped as shown at V^3 which when the feed and hammer mechanism is in normal position and type operating levers are actuated by the depression of a key or keys are pushed out of position, in numbers corresponding to the numbers of type operating levers which are actuated, by the pieces I which when moved by the type levers A^3 A^9 move the said pieces I into vertical position in numbers corresponding with the numbers of levers actuated. See the dotted positions I in Fig. 2. The said rods V^2 are thereby moved over and into engagement with a cross bar or part V^4 of a double lever V^3 which is pivoted at i^2 to a part of the machine frame or bed.

From the ends of the levers V^3 project at even distances pins v^{10} which have a loose engagement with and pass between the spurs of the spur wheels Q ; and similarly projecting from the ends of the levers I^1 bearing the feed set pieces I are pins v^{11} which pins are placed in said levers at a little greater distance from the pivot i^2 than are the pins v^{10} in the levers V^3 , from such pivot; the said pins v^{11} also passing between the spurs of said spur wheels Q and having a frictional engagement therewith when the power is set in operation. Pivoted to the machine frame at w is an arm or pendulum W which is provided with circularly arranged teeth w^1 which mesh with similar teeth w^2 of an arm W^1 which is pivoted at w^3 and bears a cross bar or plate w^4 and longitudinal ridges w^5 preferably V-shaped, which when the type is set and the pendulum W swung pass into the nicks between the type upon the type supports and lock the same in alignment. To the pendulum W is attached an adjustable weight w^6 , Fig. 2, and secured to the said pendulum is a spring actuated catch W^2 which is adapted to loosely engage by means of its tooth a stay piece w^7 . The said piece W^2 is provided with a lug w^8 which when the pendulum W is held in set position, is in position to be operated upon by a part w^9 of a piece w^{10} secured to and movable with

- the lever R^1 . To the pendulum W is also attached an adjustable piece W^3 which is fitted with inclined projectors w^{11} and w^{12} , the projection w^{12} being adapted with the forward swing of the pendulum W to pass under and raise the catch q^3 of the governor head Q^3 , to allow the power mechanism to complete its arrested revolution, to cause impression and operation of the carriage feed.
- 10 The part w^{11} passes over the said catch and thereby prevents it from being raised higher than to clear the step q^7 of the piece q^4 . To the pendulum W is movably attached at x a connecting rod X which by means of an elongated slot x^1 loosely engages a pin x^2 which is secured to the lever I^1 , Fig. 2.
- 15 The word keys used in this machine are preferably attached to a stem c^5 , see Figs. 9 and 10, which stem is split at its end forming projections y , which are embedded in the body C of the said key. The surface of the key is preferably depressed to receive a thin piece y^1 of paper, celluloid or other substance, on which the words are imprinted. A covering of thin celluloid, glass or other transparent substance y^2 is placed over the piece y^1 , and may be fastened in place by any suitable means as shown at y^3 .
- 20 Between the heads of the hammers V and the paper and the type supports A^1 is preferably placed a rubber strip Z . Fig. 2, which is attached to the carriage and runs horizontally therewith, back of the elongated opening k^9 in the said carriage, Fig. 1. A thin spring z is also secured on the inside of the carriage, one to each hammer V , and is provided with openings or holes through which the ends of the hammers may protrude when striking until their force is expended, when the spring z reacts against the shoulders z^1 of the hammers and moves them back a sufficient distance to prevent them from exerting a pressure upon the rubber Z and the paper.
- 25 If it is desired to produce a word in ordinary use the position of such word upon a key is noted when formed, and if in other position than the first upon a key, a shift key corresponding in number with the position of such word, and in appearance with the style of type, shade or color of background of said word, is depressed, (the first column of shift keys D^1 being used when the word occurs above the line C^1 , and the second column of shift keys D^1 being used when a word occurs below the dividing line C^1 on any key), which shifts the position 30 of all the transverse bars B^1 to bring their pins b^3 in position above the type operating levers A^4 , see Fig. 1; when, as the said word key is depressed, the pins arranged at various heights to represent the characters 35 in said designated word (the levers A^4 each bringing a different type into printing position according to the depth of their depressions) depress the said levers to different depths and cause an assembling of type corresponding with the length of said pins and the depression of such levers thereby, when a transverse bar B^1 is seated on the frame A^5 . According to the shift keys D^1 which may be depressed, the gauges d^1 d^8 limit the downward movement of said shift keys according to their length of movement, and thereby limit the movement of the frame B and the transverse bars B^1 .
- 40 When a transverse bar B^1 begins to descend by a pressure upon one of the keys, without or with the synchronizing mechanism D , d^2 , see Fig. 8 (detail), the under edge of said transverse bar, bearing down the lever R^2 R^1 (and at the same time the type operating levers by means of pins b^8 45 which set the type supports), which by means of its end r , bearing up against the catch q^8 thereby raises the said catch from the step q^5 , when the aforescribed power mechanism and governor is set in operation.
- 45 With the first depression of the type operating levers by the depression of said word key, the point i of the part A^9 of the said levers turns immediately and with the slightest movement to a vertical position, the pieces I which as described are of different lengths, their said lengths being relative to the position of the type operating levers.
- 50 As many of the pieces I are moved to a vertical position as there are type levers operated, thus, if four type levers were operated, as here shown, four of the pieces I will be turned to a vertical position, see Fig. 45.
- 55 The movement of the pieces I to be in a vertical position, see Fig. 2, shifts as many of the rods V^2 according to their relative positions, onto and in engagement with the lever V^3 as there are pieces I actuated, (the rods V^2 being held in normal position each by springs z^2). As the power mechanism is set in motion, the curved edges of the spurs Q glide against the pins v^{11} of the lever V^3 , and immediately thereafter against the pins v^{10} of the lever I^1 , this moving the said levers until their pins are held upon the points of the said spurs, which movement of the said levers causes the pieces I to move upward and against the edge i^5 of the plate I^3 . The said pieces move upward freely a given number of spaces corresponding to the lengths of the pieces I which are set, and, until the end of the longest piece 120 I which is set touches against the edge i of the plate I^3 which causes the said plate to move upward with the movement of the lever I^1 , until the said levers have moved their full distance and are held by their pins 125
- 60 130

in the position aforesaid. The movement upward of the pieces I from the time the longest of the said pieces I, set in vertical position, causes a movement upward of the plate I^3 a number of spaces corresponding with the position the longest piece I and one space more in numbers than the number of such pieces I set in vertical position. Thus, if the piece i^8 alone were set by the operation of the first type operating lever, its action on the plate I^3 throughout the entire movement of the lever I^1 would be of sufficient length and would act upon the said plate I^3 for a sufficient distance to produce two spaces, the lever i^7 correspondingly would produce three spaces, the lever i^8 , four spaces, the lever i^9 , five spaces, and so on throughout the whole number of pieces I. When the plate I^3 is thus actuated, it moves the friction clutch J^4 around the friction wheel J^5 a number of spaces corresponding with its movement. During the same period of its operation the pieces V^2 which have been shifted onto the lever V^3 by the pieces I, are forced upwards by the lever V^3 and through the bell cranks V^1 draw back hammers V against the springs V^6 . When the mechanisms have reached these positions the governor catch q^8 has revolved around the incline q^6 until stopped at the catch step q^7 , when, as the bar B^1 becomes entirely seated upon the frame a^5 , the extreme movement of the lever $R^2 R^1$ displaces the catch W^2 from the stay w^7 which allows the pendulum W to swing forward, when the inclined projection w^{12} , passing beneath, the governor catch q^8 raises the same from the step q^7 , which allows the power mechanism to continue its motion, and the governor head to complete its revolution, until stopped at the step q^5 . As the mechanism is thus set in operation by the pendulum W (the alignment lock w^5 locking the type supports which have ceased to vibrate during the forward movement of the pendulum W) the pins v^{11} of the lever V^3 , being at a slightly further distance from the pivot i^2 than the pins v^{10} of the lever I^1 are from the said pivot i^2 , the said lever V^3 by means of the straight edge of the spurs Q first slipping the pins v^{11} , jumps back to its normal position by the action of the hammer spring v^6 which then throw the hammers set against the type supports, when by means of the acting spring z , the said hammers after striking, rebound sufficiently to allow the forward movement of the carriage which immediately follows, by the reaction of the spring I^6 upon the feed mechanism and the lever I^3 which is allowed to return to its normal position by the point of the spurs Q slipping the pins v^{10} of the said lever I^1 . The key and transverse bar being allowed to return to their normal position by the action of the carriage c of the said bars and the

springs s^2 of the levers A^3 , the said levers A^3 are also returned to their normal positions, which allows the return of the pieces I and the pieces V^2 to their normal positions—when the lever I^1 as described returns to its normal position, the pin x^2 , Fig. 2, operating in the slot x^1 of the rod c forces by means of said rod the pendulum W back into engagement with the stay w^7 .

Since the first type support is provided with the numerals, punctuations and other characters, as shown in Fig. 51, to bring such single characters into use, a shift of the lever G, as previously described, Figs. 44, 57 and 58, will so shift the lever A^{3*} that it will disengage the second type support, and engage the first type support bearing said characters, see the levers A^{3*} , A^9 shown in dotted lines Fig. 44.

The first position feed set piece I may be made broad to accommodate the said lever in shifted positions, or may be formed of two pieces of equal length as here shown.

The lever A^{3*} , A^{9*} , in normal position operates the second type support for the production of single characters, and for the production of the initial characters of words; the said second support being the first of the letter character supports. This second support may have upper case characters and all the other supports, except the numeral support, have lower case characters, and the levers A^{3*} and A^{9*} may be positioned between the first lower case support and the upper case support, and be shifted from one to the other to begin a word with either caps or small type.

For the production of single characters the first of the levers A^4 A^6 actuating the lever A^{3*} A^9 , when depressed by a single character key, as shown in Figs. 18 and 21 (when the said lever is in normal position) will cause the setting of the alphabetical characters marked upon the said keys in the manner previously set forth.

If the lever A^{3*} A^{9*} is shifted to engage with the support bearing the other characters upon the said keys, when the latter are depressed, through the said levers, the type on the said support corresponding with the character upon the key depressed, will be set. Under the first row of single character keys is an auxiliary lever Z^3 which is secured to a pivoted collar, z^* , Fig. 16, the first lever A^4 A^6 also securely fastened to said collar and pivoted upon the shaft a^5 , and movable with the auxiliary lever Z^3 .

When a single character key is depressed it first depresses the frame S^2 which by means of the converting rod S releases through the shaft r^8 the governor Q^3 and power mechanism, which operates as previously described till stopped at the catch step q^7 , and when either of the said keys becomes seated they bear down the levers R^5 ,

which release through the shaft r^8 , as described, the governor catch q^8 from the step q^7 by means of releasing the pendulum W which thereby causes the governor to complete its revolution, the impression to be made and the feed to operate, as set forth.

Combinations of small words, such as phrases, &c., may be formed by this machine by the depression of a single key.

- 10 The spaces between the said words (since the total number of characters in such phrases or groups cannot exceed the total number of alphabetical series of type operated by the mechanism of the machine) 15 are formed by merely omitting a pin, or pins, in the transverse bar or bars for forming such groups of words, one pin being omitted in its proper position for each space occurring between words, in such groups 20 thereof. This omission of a pin thereby causes a non-action of the lever and type support in any position corresponding therewith.

A spring z^4 is preferably connected with the lever D^8 and the machine frame or bed, the object of this spring being to return the transverse bars B^1 and frames B to their normal position after operation.

The terms "differential" and "differentially" hereinafter employed in the claims, when used with respect to the pins, which determine any particular combination of characters to be set to spell a word or words are used to indicate that the said pins are 35 different or "differential" in length, i. e. their end surfaces, upon which the levers coact to set the type, are disposed at different distances from a given normal line, such, for instance, as the straight edge of a transverse bar, some pins projecting but slightly beyond said edge and others projecting all 40 intermediate or "differential" distances, in steps, therefrom to the surface ends of the longest pins; the above terms as applied to 45 the setting of the type, are used in the sense, that, during the formation of type into different words at different times, each different word causes a "different" or "differential" lot of type carried by the type supports 50 to set for the formation of one word as in contradistinction to the characteristic grouping of the type of such supports which will be caused to assemble or set for any other word, and the use of the above terms 55 as applied to the variable or "differential" carriage feed is to indicate that the carriage at different times will be caused to move any one of several different lengths of movement, which lengths of movement will be different 60 or "differential" with respect to each other; use is made of the said terms in connection with the action of the hammers, i. e. that a different or "differential" number of hammers will be set for one word than for an 65 other word.

Having now described my invention, what I claim is:—

1. A typewriting machine comprising type supports each having a plurality of type, mechanism for operating said type supports, 70 and mechanism operating upon and coacting with said type support operating mechanism to simultaneously move a number of different separately movable characters into printing position side by side to form a word, 75 and a means to support paper to receive simultaneously impressions from all of said type supports, by the depression of a single key of said second mentioned mechanism.

2. A typewriting machine comprising 80 mechanism operating type supports, and mechanism operating upon and coacting with said type support operating mechanism to simultaneously move a number of different separately movable characters into 85 printing positions by the depression of a key, the said coacting mechanism comprising surfaces arranged at different positions of a graded series of positions, and means whereby the surfaces of one of said mechanisms are set with relation to the surfaces 90 of the other mechanism.

3. A typewriting machine comprising mechanism operating type supports, and mechanism operating upon and coacting 95 with said type support operating mechanism to simultaneously move a number of different separately movable characters into printing position by the depression of a single key, said coacting mechanism having surfaces arranged in different positions in graded series, said graded series each setting different characters, and means comprising a differentially movable connection whereby at least one of said coacting mechanisms is caused to set according to the position of said graded series of surfaces. 100

4. A typewriting machine comprising mechanism operating type supports, and mechanism operating upon and coacting 110 with said type support operating mechanism to simultaneously move a number of different separately movable characters into printing position by the depression of a single key, and means to move a different portion 115 of said mechanism into position to mechanically set characters for a different word.

5. In a typewriting machine comprising mechanism operating type supports to move a number of type simultaneously into assembled position for the production of a word or other group of characters, word keys having one or more words or groups 120 of characters upon each key, a shifting mechanism to move a different portion of 125 the setting mechanism into position, to mechanically set characters for a different word, and keys for operating said shifting mechanism.

6. A typewriting machine having word 130

keys and shift keys, one or more words or groups of characters being placed upon each of said keys, a word on a word key, and a designation on a shift key corresponding in style but differing from the other or adjacent words and designations upon the corresponding keys.

7. A typewriting machine having type supports, mechanism to operate said supports, and mechanism actuated by word keys to operate said type support mechanism to simultaneously assemble certain of said type.

8. A typewriting machine having type supports, mechanism for operating said supports and mechanism communicating with word keys, whereby the operation of said keys will cause to move into printing position combinations of type characters corresponding with a word or words upon said keys and a combination shifting mechanism communicating with shift keys, each shift key imparting a different shift to the word mechanism.

9. A typewriting machine having a plurality of independently movable type supports, mechanism arranged in parallel lines for operating said supports, transverse bars or plates crossing said mechanism, said bars being actuated by word keys to operate said type support mechanism to move a number of different type characters simultaneously into printing position.

10. A typewriting machine having type supports, mechanism for operating said supports, and mechanism for operating said type support operating mechanism, means for shifting said last named mechanism comprising shift keys, means for limiting said shifting, and a tension maintaining the normal position of said second mentioned mechanism.

11. A combination set mechanism comprising type for forming a combination of different type characters, means for simultaneously operating and assembling said type, word keys for operating said combination set mechanism to operate said type assembling mechanism.

12. A combination character setting mechanism comprising a body having projections, the said projections being arranged in series along said body, and terminating at their ends at varying distances from the body, means to slidably support said body, and means to adjust said body in the direction of its length to bring the projections of a series into operative position simultaneously, and devices arranged to be operated by said projections in different positions of adjustment of said body.

13. A word setting mechanism comprising a body having a graded series of surfaces, said surfaces being arranged in different positions with relation to each other,

movable bodies arranged to coact with said surfaces, the position of said surfaces being adapted to differentially set corresponding movable bodies.

14. A word setting mechanism comprising a body having a plurality of graded surfaces said surfaces being arranged according to a graded scale at different positions with relation to each other in the manner of steps, and other series of surfaces comprising certain surfaces of the first mentioned surfaces and constituting thereby series of surfaces all arranged parallel to each other.

15. A combination setting mechanism comprising type assembling mechanism, a body having adjustable pins placed therein, said pins adjustable to different lengths of projection from said body to simultaneously operate said type assembling mechanism, and means for operating said body.

16. In a typewriting machine having type supports, movable connections to operate said supports, mechanism comprising a plurality of slidable bodies each having a series of projections terminating at their ends at varying distances from the bodies for actuating said type support operating mechanism for moving said supports to bring a number of type simultaneously into printing position side by side to form a word, and means to support paper to receive impressions from all of said type supports.

17. A typewriting machine having type supports, mechanism comprising a plurality of slidable bodies each having a series of projections terminating at their ends at varying distances from the bodies for operating said supports, said mechanism having character keys, the said keys coacting with said type support operating mechanism to simultaneously set a plurality of characters side by side on a line into a word, and means for simultaneously impressing such set characters.

18. A typewriting machine having type supports, members to operate said supports, movable transverse bars or plates crossing said members, projections between said levers and bars or plates upon which one of said sets of parts are adapted to bear to actuate the members, and by the movement of a single word key to simultaneously move a number of type characters, corresponding to a word upon the key depressed, into printing position.

19. In a typewriting machine, type supports having series of type, the line of movement of said supports being across the line of writing, and mechanism arranged to shift the normal position of the said supports to set simultaneously any characters of a designated word or group of characters in operative position.

20. A typewriting machine having a plurality of type supports bearing type, mechanism operating each of said supports, said mechanism movable to different positions, 5 said different positions each bringing a different set of type simultaneously to printing position, transverse bars crossing said mechanism, and means between said mechanism and transverse bars to actuate said mechanism and type.

21. A typewriting machine having type supports, means for operating said supports, transverse mechanism for simultaneously operating said type support operating mechanism, means for holding the mechanism operating said transverse mechanism in normal position, and means for imparting a designated movement to said transverse mechanism.

22. A type support, mechanism connected with and operating said support, a plurality of keys supported independently of said mechanism and having a bearing thereon, said keys having each an independent motion, and means for limiting the depth of movement thereof to move a designated type into printing position.

23. A type support, a pivoted lever connected with and operating said support, an auxiliary lever connecting with and operating said first named lever, a plurality of keys arranged along each of said levers and having a bearing thereon, said keys having each an independent motion, and means for limiting the depth of movement thereof to move a designated type into printing position, substantially as set forth.

24. In a machine having type and means for simultaneously assembling same, a key board for operating said type for producing designated single characters, and keys for producing designated complete words.

25. In a machine having a plurality of type supports, manually operated keys, and means interposed between said keys and type supports and comprising slidable bodies having a series of projections of varying length for simultaneously assembling said type supports, a plurality of impressers arranged 50 in a longitudinal plane and adapted to be operated to impress such simultaneously set characters by the operation of said machine.

26. In a typewriting machine having a plurality of independently movable type supports, and means for assembling and operating simultaneously a plurality of said movable supports, a plurality of impressers arranged for said type supports and means comprising word keys and a self differentiating selecting and setting mechanism to simultaneously actuate a plurality of said type and said impressers to impress a designated word by the action of a key.

27. In a typewriting machine having a plurality of independently movable type

supports provided with type, means for mechanically assembling simultaneously a plurality of said type supports, a plurality of impressers arranged adjacent to each other and means comprising word keys and self differentiating selecting and setting mechanism to actuate a plurality of said type and said impressers, the number of said impressers so actuated corresponding with the number of type so set for a word by the action of a key.

28. In a typewriting machine having a plurality of independently movable type supports, means for mechanically assembling simultaneously a plurality of said type supports, and means comprising word keys for actuating the same, a plurality of impressers arranged with relation to said type and corresponding in number with the number of said type supports, said type and said impressers being actuated by a self differentiating selecting and setting device to automatically set and impress a word.

29. In a machine having a plurality of independently movable type supports, and means for simultaneously automatically and differentially assembling and operating the same, a plurality of impressers, means comprising word keys and a self differentiating and actuating means to automatically and simultaneously operate the said type supports and said impressers.

30. In a type assembling and writing machine having a plurality of impressers, means comprising word keys for setting certain of said impressers with the movement of the said type and means for releasing the said impressers when said type are set.

31. In a machine having type and a plurality of movable bodies for impressing said type, means comprising word keys whereby one or more of said movable bodies are set for impressing with the setting of said type, the said movable bodies set corresponding in number with the number of type set for impression, the setting of said type and said movable bodies being actuated by an automatic, self differentiating selecting means.

32. In a type assembling and writing machine having a variable feed actuating mechanism and a plurality of impressers, a means comprising word keys whereby the actuation of said feed mechanism causes the setting of said impressers, and means comprising a self differentiating selecting feed and impresser setting device, the number of impressers set corresponding to the number of spaces moved for the word by said feed.

33. In a typewriting machine having a plurality of type supports, impressers, and word keys, said impressers consisting of a series of bodies arranged adjacent to each other and adapted to be moved singly and collectively by the operation of said word keys, a self differentiating setting device to

- set said type supports automatically simultaneously into a word, the said setting device causing a differential action of said impressers. 65
34. A typewriting machine having type supports, a feed mechanism and a plurality of impressers, a power mechanism for operating and a mechanism engaging said impressers, said second mentioned mechanism being normally disengaged from said power mechanism and adapted to be moved into engagement therewith by the operation of the type support mechanism. 70
35. A typewriting machine having type supports, a feed mechanism and a plurality of impressers, a power mechanism for operating said impressers, a bell crank for engaging each of said impressers, laterally and longitudinally movable rods connected with 75
- 20 said cranks, and means whereby the setting of said feed mechanism moves a certain number of said rods out of normal position and into engagement with said power mechanism to actuate said impressers, also 80
- 25 a tension means for operating said hammers, 85
36. In a typewriting machine having an impression impresser, a power device for actuating said hammer, mechanism for operating said impresser, said mechanism consisting of movable connections with said impresser and a lever for operating said impresser, said lever having a frictional contact with a spur wheel operated by a power device. 90
37. In a machine having type and means for simultaneously assembling same, means for producing a word or other group of characters by the movement of a single key, and having a variable paper feed mechanism, and means to return the paper reversely to its variable feed. 95
38. In a typewriting machine having type supports and mechanism for operating said supports, a combination set mechanism for 100
- 45 operating said type supporting mechanism, said combination set mechanism comprising an elongated body having pins arranged in a plurality of series, the said pins being of varying lengths, all of the pins of one series 105
- 50 being adjacent to each other. 110
39. In a machine having type, and means comprising parallel bodies for assembling said type, and mechanism arranged transversely to said parallel bodies and adapted to 115
- 55 coact therewith, to simultaneously operate said parallel bodies, the said parallel bodies being less in number than the transverse pieces. 120
40. In a typewriting machine having type supports, and mechanism for operating said supports, a combination set mechanism for 125
- 60 operating said type supporting mechanism, said combination set mechanism comprising an elongated body having projections of graded lengths and means for operating the same. 125
41. A combination set mechanism comprising a movable member, and a body having pins or projections, the said pins terminating in different positions, the aforesaid members being movable toward the ends of said pins, and depressing different depths corresponding to the difference of position occupied by the ends of said pins. 130
42. In a machine having a plurality of supports, each having a plurality of type, and means for simultaneously assembling said type, word keys, a number of movable bodies arranged to impress said type assembled by the action of a word key, the said movable bodies corresponding in number to the number of type supports. 135
43. A typewriting machine comprising type supports, mechanism for operating said type supports, certain of said supports having each a complete alphabet of type, hand or finger keys, and mechanism operating upon and coacting with said type support operating mechanism to simultaneously move a number of type characters into a line 140
- 90 for printing position, thereby mechanically spelling words or phrases by the depression of a hand key or of one or more single keys, which are adapted to be actuated by the operator. 145
44. A typewriting machine having type supports, means for operating said supports to move type into assembled position for printing, and a carriage feed set automatically to correspond with the number of type 150
- 100 set and one space more by and during the movement of said type support operating means, said carriage moving a number of spaces corresponding to one space more than the number of type characters in a word. 155
45. A typewriting machine having type supports, and character keys, mechanism for bringing types on said supports to a printing position to produce a group of characters, a carriage and a feed operating mechanism therefor arranged to move the carriage by the operation of a character key a space corresponding to one space more than the number of characters in a group set by such character key. 160
46. In a typewriting machine having a plurality of independently movable type supports adapted to be set simultaneously for the impression of a word by the depression of one or more character keys, a carriage movably connected with the machine, a variable feed adapted to move the carriage a number of spaces corresponding with or one space more than the number of characters in a set word, an automatic release for disengaging said carriage from the feed mechanism when at the end of a line, and a means for automatically throwing said auto- 165

matic release and feed mechanism out of and into engagement coincident with the extreme movement of the carriage in either direction, all by the operation of finger keys.

5. 47. In a writing machine having a carriage, and means for assembling a plurality of type simultaneously for the formation of words, a self differentiating feed device to feed said carriage the space of the combined 10 characters of a set word, and automatic release mechanism to release said carriage during its forward travel, said release device being actuated by the action of a self differentiating word space feed, and a back 15 acting tension adapted to return the carriage to its starting point, all with the operation of word keys.

48. In a writing machine one or more type supports and a paper support, means 20 for operating and simultaneously assembling said type supports to bring any desired character into printing position, and a feed to move the paper support a number 25 of spaces corresponding evenly with or one space more than the number of characters contained in a set word, the said means for moving said carriage being actuated by word keys.

49. In a typewriting machine having a 30 number of separately movable type supports to be simultaneously assembled by the action of a key, means for supporting paper, means for moving said paper, consisting of a variable feed, a wheel to operate 35 said feed, and mechanism to operate said wheel to impart different movements to said feed by the operation of a character key.

50. In a writing machine having a number of separately movable type supports 40 adapted to be simultaneously assembled by the action of a key, a variable feed, mechanism for operating said feed to move the same number of spaces corresponding with the number of characters set, and means for 45 automatically locking said feed.

51. In a typewriting machine having a plurality of type supports, mechanism for operating said supports, and a mechanism for simultaneously actuating said type supports 50 operating mechanism to assemble characters, a carriage, and a variable feed operated by said type assembling and actuating mechanism, said variable feed being arrested and actuated to move one space more 55 than the number of characters assembled for a word.

52. A typewriting machine having type supports, means for operating said supports, a carriage, a number of movably supported pieces constituting a portion of a carriage feed, each movable piece in the order of its position causing the carriage to move a number of spaces corresponding with the number of spaces in a word for 60 which said movable pieces are set, means

for setting one or more of said pieces, and means for simultaneously moving said set pieces to actuate other mechanism, said other mechanism when actuated causing a forward movement of a paper bearing carriage. 70

53. In a typewriting machine having type supports, means for operating said supports, a carriage, pieces of different and graduated lengths movably supported, each 75 movable piece in the order of its position causing the carriage to move a number of spaces corresponding with the number of spaces in a word for which said movable pieces are set, said pieces actuated by said type operating mechanism, and mechanism operated by said movable pieces to move forward a paper bearing carriage a number 80 of spaces corresponding with the arrangement and length of said movable pieces, also means for simultaneously moving said movable pieces. 85

54. A typewriting and assembling machine having type supports, and means for operating said supports, a variable feed 90 mechanism consisting of a number of movable pieces, said pieces being of different and graduated lengths and corresponding in number with the number of type supports, and being set by the actuated mechanism, and means for simultaneously moving said movable pieces to actuate the forward 95 movement of a paper carriage.

55. A type assembling and writing machine having type supports and means for operating said supports, a variable feed 100 consisting of a plurality of movable pieces, a lever supporting said pieces, means for actuating said pieces, a mechanism for actuating said lever, and a means whereby a simultaneous movement is imparted to said pieces to actuate the forward movement of a paper bearing carriage. 105

56. In a variable feed a lever having 110 pieces movably and independently supported thereon, the said lever adapted to move said pieces simultaneously, and a frictional part formed upon said lever to actuate it by means of a force mechanism.

57. In a variable feed consisting of a number of separately moving pieces, and a means for setting and simultaneously moving said pieces, a mechanism differentially 115 movable relatively to the action of said pieces, said mechanism being actuated thereby to move forward a carriage. 120

58. In a machine having a plurality of independently movable type supports and means for simultaneously setting and impressing the same, a carriage, a differential carriage feed comprising a movable body, means for imparting movement to said body, said means comprising in part a simultaneous setting of a plurality of said 125 type supports, a mechanism actuated by 130

- 5 said movable body to feed said carriage, a re-acting tension connected with said carriage, and means whereby said feed disengages said carriage at a determined point by the operation of a plurality of said type supports, comprising a disengaging means whereby said tension acts to return said carriage to its original position.
- 10 59. In a machine having a plurality of independently movable type supports and means for simultaneously setting and impressing the same, a carriage, a differential carriage feed comprising a movable body, means for imparting movement to said body, said means comprising in part a simultaneous setting of a plurality of said type supports, a mechanism actuated by said movable body to feed said carriage, a re-acting tension connected with said carriage at a determined point by the operation of a plurality of said type supports, and means comprising a disengaging means whereby said tension acts to return said carriage to its original position.
- 15 60. In a word writing machine a plurality of independently movable type supports, means for simultaneously operating a plurality of said supports, a carriage, a self differentiating feed device, connection for causing the differential engagement of said feed device with said carriages during the forward movement thereof, and means comprising a differentially actuated release to disengage said feed from said carriage, combined with means comprising a tension for returning said carriage to its original position.
- 20 61. In a word writing machine having a plurality of independently movable type supports, means for simultaneously operating a plurality of said supports, a carriage, a self-differentiating feed device, having engagement with said carriage during its forward movement, means comprising a differential operated release to disengage said carriage, and an automatic action for causing said feed to so disengage said carriage by its movements.
- 25 62. A word writing machine having a plurality of independently movable type supports, means for simultaneously operating a plurality of said supports, means comprising a differential set device to differentially set said type supports, a carriage, a self differentiating feed comprising means for movably engaging and actuating a laterally movable rack connected with said carriage, means comprising a shift for laterally moving said rack, and reacting means for reversing the longitudinal action of said rack, said feed device actuating the movement of said rack.
- 30 63. In a typewriting machine having a plurality of independently movable type supports, means for simultaneously operat-
- 35 ing a plurality of said supports, a carriage, a self differentiating feed mechanisms for actuating said carriage, including a device comprising differential steps operated by said first named means, said latter device operating in connection with said feed to differentially limit its movement.
- 40 64. In a typewriting machine having a plurality of independently movable type supports, means for simultaneously operating a plurality of said supports, a carriage, a self-differentiating feed mechanism, said mechanism comprising a movable piece, said piece having differentially arranged steps, mechanism comprising a connection actuated by said piece to differentially actuate said carriage, said carriage having a differential feed motion corresponding to the differential movement of said movable piece.
- 45 65. In a writing machine one or more type supports and a paper support, means for operating and simultaneously assembling said type supports to bring any desired character into printing position, and a feed mechanism, to move the paper support a number of spaces corresponding to one space more than the number of characters contained in a set word, the said means for moving said carriage being actuated by said first named means.
- 50 66. In a machine having a plurality of separately movable type supports, a key and means controlled thereby to operate a group of said supports to assemble a plurality of type side by side, and single character keys to control the operation individually of some of said supports to set single type.
- 55 67. In a machine having type supports and means to operate said supports, a carriage, means to operate said carriage, and a differential margin spacing mechanism adapted to move the carriage operating means to shift the carriage varying marginal distances.
- 60 68. In a machine having type supports and means to operate said supports, a carriage, means to operate said carriage, a differential margin spacing mechanism adapted to move the carriage operating means to shift the carriage varying marginal distances, said mechanism comprising a key variously movable to different positions.
- 65 69. In a machine having type supports and means to operate said supports, a carriage, means to operate said carriage, and a differential margin spacing mechanism adapted to move the carriage operating means to shift the carriage varying marginal distances, said mechanism comprising a member movable manually and a stop device having a plurality of surfaces disposed in different planes to determine the movement of said member.
- 70 70. In a machine having type supports and means to operate said supports, a car-

riage, means to operate said carriage, a differential margin spacing mechanism adapted to move the carriage operating means to shift the carriage varying marginal distances, said mechanism comprising a key variously movable to different positions and a stop device having a plurality of surfaces to arrest the movement of said key.

71. A typewriting machine having type supports, keys, mechanism to operate said supports, and mechanism actuated by multiple character keys simultaneously assemble certain of said type into a plurality of groups of characters with spaces simultaneously produced between said groups of characters.

72. A typewriting machine having type supports, word keys, mechanism to operate said supports, and mechanism actuated by word keys to operate said type support mechanism to simultaneously assemble certain of said type into a plurality of words with the word spaces simultaneously produced between said words.

73. A typewriting machine having a capital type support and a plurality of lower case type supports, word keys, mechanism to operate said supports, and mechanism actuated by word keys to operate said type support mechanism to simultaneously assemble certain type, means comprising a shift device to operatively engage and disengage said capital case type support with relation to said lower case type supports.

74. A plural type group forming mechanism comprising a body having graded surfaces, said surfaces being arranged in different positions with relation to each other, movable bodies arranged to co-act with said surfaces, the positions of said sur-

faces being adapted to differentially set the corresponding movable bodies to produce plural groups of characters with blank spaces disposed between said groups.

75. In a type assembling and writing machine having a plurality of type supports and a plurality of impressers, means comprising word keys for automatically operating said impressers, and means for manually operating certain of said impressers to impress single type.

76. In a machine having type supports, a paper support, means for operating, assembling, and impressing a plurality of type of said supports into groups of characters and a feed mechanism to move the paper support forward a number of spaces corresponding evenly with or one space more than the number of characters contained in a type group, means whereby said feed mechanism is automatically disengaged from the said support, the impressing of the finally set type group completing a predetermined length of line of writing, and means to cause the paper support to be returned to the beginning of a line.

77. In a machine having type and means for assembling the same, and having word keys and single character keys, and means for producing a word or other group of characters, word-spacing paper feed mechanism, and means to cause the paper to feed forward one step at a time by the operation of a single character key when operating a single character.

Signed at New York city, in the county of New York, and State of New York, this 17th day of April, A. D. 1922.

CLYDE C. BALSTON.
